GEORGE R. BARKSDALE, OF STRATFORD, ONTARIO, CANADA.

DISK-GRINDER ATTACHMENT.

1,419,535.

Specification of Letters Patent. Patented June 13, 1922.

Application filed November 19, 1920. Serial No. 425,246.

To all whom it may concern:

Be it known that I, GEORGE R. BARKSDALE, a citizen of the United States of America, residing at Stratford, in the county of Perth, Province of Ontario, and Dominion of Canada, have invented a new and useful Disk-Grinder Attachment, of which the following is a specification.

My invention relates to improvements in attachments for disk grinders, and consists generally of a rotatable and reciprocable shaft provided with certain peculiar work-holding means, and certain peculiar means or mechanism for controlling and operating said shaft, all as hereinafter set forth.

The primary object of my invention is to provide a comparatively simple and inexpensive, yet strong and durable, attachment for use in connection with grinders of the class specified above, whereby a large production at a low cost, and an excellent grade of work as well, are obtained, and wherewith the pressure of the casting being ground on the grinding disk can be kept uniform and as great as may be desired. If the pressure be too light, the abrasive material on the grinding disk becomes "glazed," since in that case it cannot clear itself of the small particles produced by the friction incident to the grinding operation, and the abrasive effect of said disk is greatly reduced. The life of the grinding disk is, therefore, prolonged by the use of my attachment, and this may be said to constitute another object of my invention.

A further object is to afford means whereby is entirely obviated the liability of too forcibly thrusting the casting to be ground against the grinding disk and thereby seriously damaging the disk or its abrasive material.

The holder with which my attachment is equipped is adapted to accommodate castings having irregular shapes, and the attachment as a whole is capable of being used with all types of disk grinders.

The operator who uses this attachment is relieved of the strain which has in some cases heretofore existed in connection with grinding on a disk grinder, so that a girl can with said attachment do the work which frequently has required the services of a man.

The attachment is adjustable so as to

enable work of any thickness desired to be ground, within certain regular or natural limitations.

Other objects and advantages will appear in the course of the following description.

A preferred embodiment of the invention, whereby I attain the objects and secure the advantages of the same, is illustrated in the accompanying drawings, and I will proceed to describe the invention with reference to said drawings, although it is to be understood that the form, construction, arrangement, etc. of the parts in various aspects are not material and may be modified without departure from the spirit of the invention.

In the drawings, in which like numerals designate like parts throughout the several views, Figure 1 is a central, longitudinal, vertical section through a disk-grinder attachment which embodies a practical form of my invention as aforesaid, the disk of the attachment and the holders carried thereby being in elevation; Fig. 2, a side elevation of the working face of the cam; Fig. 3, a detail, in section, of the piston-head terminal of the shaft and associated parts and members, showing a spring substituted for the compressed-air means whereby the cam on said shaft is retained in contact with the abutments therefor; Fig. 4, a transverse, vertical section through said attachment, taken on lines 4-4, looking in the direction of the associated arrow, in Fig. 1; Fig. 5, an enlarged, exterior, broad-side elevation of one of the work holders, and, Fig. 6, a central, transverse, vertical section through said work holder, on lines 6-6, in the direction of the associated arrow, Fig. 5, a fragment of the disk to which said holder is attached also appearing.

Although I have shown as the preferred form pneumatic or compressed-air means for urging the reciprocable members forward and retaining the cam on the revolvable and reciprocable shaft in yielding contact with the abutments provided therefor, it is obvious that a spring might be utilized for the same purpose, but it is equally obvious that yielding means of the character of a spring would be much less efficient than yielding means of the pneumatic type, and that it would be much more difficult to change or adjust the amount of compression to meet different conditions in the case

of the former than in the case of the latter, it being much easier to adjust the reducing valve in a compressed-air line than to take out a spring and insert a weaker or a 5 stronger one, as the case may be, in the place of the first. Nevertheless, I do not wish to be confined exclusively to the pneumatic control or yielding means for the reciprocating members, and will make use of 10 a spring if for any reason it appears to be desirable to do so.

I have shown the work-holder disk equipped with three work holders, and most frequently such will be the number employed, although in some cases it may be 15 desirable to use less and in other cases even more than that number. Ordinarily, if more than three work holders were provided on the disk, the castings held by such holders 20 would not remain a sufficient length of time in contact with the abrasive material of the grinding disk to enable such castings to be properly ground, and limitation to a single work holder would materially reduce the 25 speed efficiency of the attachment.

Referring to the drawings, it will be observed that my attachment comprises a suitable supporting frame 1 having at the top 30 bearings 2-2, with bushings 5-5 therein, the space between said bearings extending downwardly to form a cleft 7 in said frame, and the latter having also on top a seat 3 for a cylinder 8; a horizontal shaft journaled 35 in said bushings and extending into said cylinder, the right-hand terminal of said shaft being in the cylinder, since the latter is at the right of said bearings; a worm-wheel 10 mounted on said shaft; a piston on the terminal of said shaft which is in said 40 cylinder, and a work-holder disk 11 on the opposite terminal or end of said shaft; a cam 12 secured to said shaft between the inner end of said cylinder and the adjacent end of the right-hand bearing 2; a plurality 45 of abutments for said cam, and an equal number of holders on said disk. There are three cam abutments in the present case, although such number may vary and in any event should agree with the number of work 50 holders, of which latter there are three in the present case, as hereinbefore observed.

The worm-wheel 10 revolves through the cleft 7 in the frame 1, and the cam 12 revolves through a recess 13 with which said 55 frame is further provided. The worm-wheel 10 is driven in the usual manner, and in turn drives the shaft 9 and with it the disk 11 and the work attached thereto and carried thereby. The shaft 9 is not only 60 revolvably but also reciprocably mounted or journaled in the bearings 2 or the bushings 5 therein, the reciprocating movement of said shaft being permitted by reason of the fact that the hub of the worm-wheel 10 fits 65 between the bearings 2 and bushings 5,

and said worm-wheel or hub is secured to said shaft by means of a key 14 which is seated in said shaft and extends into a longitudinal slot 15 in said hub, (a portion of the shaft being broken away in Fig. 1 70 to show said key in full.) said slot being longer than said key, and extending beyond the same at both ends. A limited amount of axial movement is thus permitted to the shaft 9 without interference therewith on the 75 part of the worm-wheel 10, although the two members are connected so that they must revolve together.

The inner end of the cylinder 8 is closed by means of a stuffing-box 16 which is 80 tapped into such end, a gland 17 which is tapped into the inner or open end of said stuffing-box, and stuffing 18 in the stuffing-box. Thus the terminal of the cylinder, which is around the terminal of the shaft 85 9 that extends into said cylinder, is securely closed. There is an opening in the center of the outer, closed end of the cylinder 8 for the introduction into said cylinder of compressed air through a pipe 19 that forms 90 part of a compressed-air line or system. In the top of the cylinder 8 is an opening for a pipe 20 through which oil may be introduced into said cylinder, and in the bottom of said cylinder is an opening for a pipe 21 95 through which oil may be drawn out of the cylinder.

The piston on the piston-head of the shaft 9, to which reference has been made, comprises a supporting disk 22 and a cup-packing 23 secured to said piston-head by means of a bolt 24. The end of the shaft 9 which is in the cylinder 8 is turned down to form a projection or hub 25 on which the supporting disk 22 is mounted, and the bolt 24 is 105 tapped into and through said projection and into the main body of the shaft.

From the foregoing it is clearly to be seen that air under compression in the cylinder 8 between the closed or outer end of said cylinder and the cup-packing 25, or in other words, behind said cup-packing, tends constantly to urge the piston, of which said cup-packing constitutes a part, to the left, and with it the shaft 9 and the parts and members that are rigidly attached to said shaft. The force exerted on the piston by the compressed air in the cylinder 8 may be varied in the usual manner, just as in any other compressed-air apparatus which is provided 110 with a reducing valve.

Neither the compressed-air apparatus, system, or line, or the driving means for the worm-gear 10, is herein shown, since both are mechanical elements so well understood as to need no illustration, and inasmuch as they constitute no direct part or element of or in the present invention.

Oil is introduced through the pipe 20 into the cylinder 8 to prevent leakage of air 130

therefrom, and may be drawn out of said cylinder through the pipe 21 whenever occasion demands.

The cam abutments, of which mention has been made, consist of three horizontal rods 26 provided with a corresponding number of rolls 27. Each rod 26 is tapped into and through a lug 28 which is integral with the inner or right-hand bearing 2, and has thereon at each end of said lug a nut 29 to secure said rod in place and permit the same to be longitudinally adjusted. And each rod 26 is provided at the right-hand end with a bifurcated head 30 connected with which is one of the rolls 27, such roll being mounted on a spindle 31 which is journaled or mounted in the arms of said head, and is radial to the axis of the shaft 9. The lugs 28 are equi-distant from each other and the rods 26 are so arranged or adjusted in said lugs that the peripheries of the rolls 27, behind or at the right, touch a common vertical plane. The cam 12 is in operative position relative to the rolls 27, and said cam has on and in the working face thereof, which is the face or side that is adjacent or contiguous to said rolls, three elevations 32 and the same number of depressions 33. The elevations 32 and consequently the depressions 33 are equi-distant apart on the working face of the cam 12, and said elevations are all alike, as are said depressions. The rolls 27 as previously stated, are equi-distant apart in the circle in which they are located, which circle is concentric with the cam 12 and the shaft 9. The cam 12 is secured to the shaft 9, in proper position relative to the abutments, by means of a horizontal key 34, and a tapered pin or key 35 that is driven into and through said shaft outside of or behind said cam, or contiguous to the face of said cam which is opposite to the working face of the same. The key 35 backs up the cam 12, so to speak, and thus reinforces the cam and insures the required stiffness thereof for a firm contact with the abutment rolls 27. In this case the cam follows the rolls 27 and moves axially, instead of the rolls, as they enter and leave the depressions 33 in the cam, being themselves caused to move in a direction other than that taken when revolving on their axes, and to carry with them the parts with which they are connected. In short, here the cam abutments, which take the place of ordinary cam followers, remain stationary, except that their anti-friction members revolve, and the cam moves on its axis lengthwise, besides turning thereon, which is just the opposite of the usual arrangement and operation of cam mechanism.

The compressed-air in the cylinder 8 behind the piston forces the shaft 9 to the left or forward and causes the cam 12 to

remain in constant contact with the cam abutments, and to reciprocate as the high and low parts of said cam ride over the rolls 27, with the result that said shaft is reciprocated accordingly. The shaft 9 both rotates and reciprocates in the stuffing-box 16 and associated parts or elements and carries with it whatever parts and members are rigidly attached thereto.

The work-holder disk 11 has a hub 36 and these are rigidly attached to the left-hand or what may be termed the forward end of the shaft 9 and are located beyond the corresponding end of the frame 1. I will next proceed to describe in detail one of the three work-holders with which the disk 11 is equipped, it being understood that any of said work-holders is the duplicate of either of the others, and that they are arranged equi-distant apart on the outer or front face of said disk.

Secured to the inner or back side or face of the disk 11 adjacent to the periphery thereof, by means of a pair of bolts 37, is a plate 38. Formed partly in the center of the plate 38 and partly in the disk 11 is a recess 39. A passage 40 extends outwardly or forwardly from the recess 39, or that part of the same which is in the disk 11, to and through the outside or front face of said disk. A bolt 41 has a globular head 42 which is received in the recess 39, and a shank that extends through the passage 40 and some distance beyond the outer face of the disk 11. The diameter of the passage 40 is somewhat larger than that of the shank or that portion of said shank, of the bolt 41, which is located in said passage, but there is a felt washer 43 which encircles such shank and tends to retain the same in a horizontal position, said washer being held in place or secured between the outside face of the disk 11 and a perforated disk or ring 44, by means of two or more bolts 45 that pass through said ring and washer and are tapped into said disk. A rectangular block 46 is screwed on to the outer terminal of the bolt 41. Rigidly secured, by means of rivets 47, to the outer face of the block 46 adjacent to the lower corners thereof are two fixed dogs 48. A movable, angular dog 49 is located in a slot 50 in the center of the upper part or portion of the block 46, which slot is radial to the axis of the disk 11. The dog 49 has an overhanging head 51, the same projecting beyond the outer face of the block 46. A face-plate 52 is secured, by means of screws 53, to the block 45 over the dog 49 in front. The overhanging portion of the head 51 of the dog 49 extends beyond the face-plate 52. A spring 54 is arranged in a passage in the block 46 and a recess in the bolt 41, provided to receive said spring, to bear against the inner end of the dog 49, and to force said dog outwardly. The block 130

46 is provided behind the body portion of the dog 49 with a stud 55, and mounted on this stud is an eccentric 56, said eccentric being held in place on said stud, against the 5 back sides or back edges of the slot 50, by means of a screw 57 which is tapped into said stud from the rear or inner end thereof, and has a head large enough to extend onto or engage said eccentric. The eccentric 56 10 is in contact with a rearwardly-extending arm 58 at the inner terminal of the dog 9, and is adapted to actuate said arm and dog inwardly against the force of the spring 54, or to permit said spring to actuate said dog 15 outwardly, according to the direction in which said eccentric is rotated on its stud 55. The eccentric 56 is provided with peripheral openings 59 for the introduction of a bar or rod (not shown) when said eccentric is operated.

Inasmuch as the bolt 41 has some movement on its head 42 which is in the recess 39, and due to the fact that the diameter of the passage 40 is somewhat larger than the 25 diameter of that portion of the shank of the bolt that is in said passage, a certain amount of movement is permitted to the block 46 carried at the outer end of said bolt. The fibrous washer 43 yields to permit the bolt 30 41 to rock, and said washer is, therefore, another factor in the independent rocking or oscillatory movement of said bolt. The aforesaid movement permits the block 46 to rock and properly adjust itself with the 35 work attached thereto to the grinding disk. A yielding support is provided between the block 46 adjacent to its inner end and the disk 11, such support being in the form, in this case, of a spiral spring 60 interposed 40 between said block and said disk, or rather between the head of a rod 61, which head bears against said block, and said disk. The headed rod 61 is slidingly mounted in the disk 11, parallel with the axis of said disk, 45 behind the block 46 near the inner end of the longitudinal center thereof, and the head of said rod is thrust into engagement with said block by the spring 60, the outward or forward movement of the rod being limited 50 by a transverse pin 62 therein behind said disk. The spring 60 encircles the rod 61 between the head and the disk 11, and the pin 62 limits the outward or forward movement of said rod under the influence of said 55 spring. The pin 62 is so placed or located in the rod 61 that the block 46 is positioned in substantially parallel relation with the disk 11, when said pin is in contact with the back side of said disk. The block may be forced 60 inwardly, against the resiliency of the spring 60, at the inner end, the bolt 41 then rocking on its head 42 and overcoming whatever resistance may be offered by the felt washer 43. As soon as the irregular pressure is 65 moved from the block 46, the spring 60 acts

to restore the parts to normal position again. Only a slight amount of movement is thus provided for, but the same is sufficient to enable the block 46 with the work carried on the face thereof automatically to adjust 70 itself to the grinding-wheel disk. Inasmuch as the block 46 is not attached to the rod 61, said block may be rocked on and with the inner bolt 41 in the direction to carry the inner end of said block away from said rod in 75 which event the rod, being spring-pressed, serves as a buffer for the block when it returns to normal position.

The broken lines at 63 represent a piece of work or a casting carried by each holder. 80 The casting 63 has a flat-iron shape, and is arranged with its apex end towards the axial center of the disk 11 and between the dogs 8, and its broad end or base within the grasp of the projecting head 51 of the movable 85 dog 49. The casting is thus located after first rotating the eccentric 56 on its stud 55 in the direction to enable the spring 54 to throw the dog 49 outwardly a sufficient distance to permit said casting to be placed 90 flat against the face of the block 46. When the casting 63 is located against the face of the block 46, in the manner just described, the eccentric 56 is actuated in the opposite direction to force the dog 49 inwardly 95 against the resiliency of the spring 54, and crowd the head 51 of said dog tightly against the base of said casting. Thus the work is held with absolute security between the fixed dogs 48 and the movable dog 49.

Pins 67-67 are set in the face of the disk 11, on opposite sides of each plate 46, to hold said plate and the bolt 41 against rotary motion about or on the axis of said bolt. The plate 46, with the bolt 41, is, therefore, 105 limited to a rocking motion or movement, between the contiguous pins 67, on the bolt head 42 in the recess 39.

In practice, the castings 63 are attached to the work holders, the power is applied 110 to the worm-wheel 10 to revolve said worm-wheel and the shaft 9, each of said castings is thrust into contact with the grinding disk or wheel (not shown) and permitted to remain the required length of time to grind 115 the exposed surface or the face of such casting, and then the latter is withdrawn from said wheel. The castings, being secured by the work holders to the disk 11, revolve with said disk as the latter is rotated with 120 the shaft 9, and each time that the low parts 33 of the cam 12 contact with the abutment rolls 27 the pressure in the cylinder 8 behind the piston forces said piston, the shaft 9, and the disk 11, with the work holders 125 attached thereto and the castings carried by said holders, forward, thus projecting, said castings into the plane of the aforesaid grinding wheel and one of the castings into contact with said wheel. When the eleva- 130

tions 32 of the cam 12 ride on to the abutment rolls 27, said cam is forced rearwardly and carries with it, against the aforesaid pressure in the cylinder 8, the shaft 9 with its piston at one end and disk at the other end, and so withdraws the castings from the grinding wheel and the grinding wheel plane. The cam 12 is so constructed and proportioned as to allow each casting to remain in contact with the grinding wheel or the grinding surface thereof long enough to complete the grinding operation on such casting, that is to say, to grind the exposed surface of said casting to the required extent.

Inasmuch as it is desired to bring the castings 63 snugly into contact with the grinding wheel, the driving and reciprocating mechanism for the shaft 9 are necessarily so proportioned relatively, or timed, that said shaft, with the disk 11, work holders, and work, is advanced and retracted three times at each revolution. A different timing and arrangement might be employed, and the arrangement might be such that all of the castings supported from the disk 11 would be ground simultaneously.

If any casting were permitted to come gradually into contact with the grinding surface or to encounter the edge of the grinding-wheel, it will be readily seen that there would be grave liability of breaking off pieces of said wheel or otherwise injuring the same or the grinding surface thereof. This liability is entirely avoided by my mechanism which causes each casting to be thrust against the grinding wheel at just the proper place and instant, and causes said casting to be withdrawn at just the right time.

After the three castings 63 have been ground, the movable parts of the attachment are stopped, the eccentrics 56 are operated to release the castings, the latter are removed, and others to be ground are placed in the holders. The mechanism is then set in motion again and the grinding operation repeated. This cycle of events may be repeated indefinitely.

The operation of releasing and removing from the work holders the castings 63, and placing other castings in said holders and securing them therein, can be done most expeditiously as well as conveniently and easily.

In order to regulate the attachment to the thickness of the work, it is simply necessary to loosen the nuts 29, screw the abutment rods 26 in whichever direction may be necessary to bring about the required adjustment, and retighten said nuts. For a thicker casting, it is necessary to adjust the abutment rods 26 to the right, so that the rolls 27 will position the foremost and rear-most, operating planes of the cam 12 and of

all of the parts and members controlled by said cam farther in that direction. Contrariwise, if it be necessary to set the mechanism for thinner castings, the abutment rods 26 are adjusted to the left, so that the rolls 27 permit the aforesaid operating planes of the cam 12 and of the parts and members controlled thereby to be located farther in said last-named direction.

As previously intimated, a spring, as 64, may be substituted for the compressed-air in the cylinder 8 back of the piston, or back of what may take the place of the complete piston when said spring is employed, namely, the supporting disk 22 of said piston—see Fig. 3. The supporting disk 22 is held in place by the same bolt 24 as before, a washer 65 being interposed between the head of said bolt and adjacent parts. Obviously the movable parts and members of this attachment operate in substantially the same manner with the spring 64 as when compressed-air is employed back of the piston head of the shaft 9. But it is equally obvious that the spring 64 does not afford the ready means of control and of varying the control of the reciprocable movement of the shaft 9 and attached parts that is afforded by the compressed air. When the spring 64 is employed it is necessary either to construct the cylinder 8 without any opening in the outer end for the compressed-air pipe 19, or to close such opening, as with a plug 66. The oil pipes 20 and 21 may or may not be retained, as desired.

What I claim as my invention, and desire to secure by Letters Patent, is—

1. In an attachment, of the class described, a revoluble and reciprocable shaft, a cam mounted on said shaft, an abutment, and yielding means to retain said cam in contact with said abutment, said shaft being provided with work-holding means.

2. In an attachment, of the class described, a revoluble and reciprocable shaft, a cam and work-holding means mounted on said shaft, an abutment, and yielding means to retain said cam in contact with said abutment.

3. The combination, in an attachment of the class described, with a frame, and a cylinder and cam abutments supported by said frame, of a shaft journaled in said frame, and extending into said cylinder, a driving member for said shaft, the latter being revolvably connected with said driving member, but having independent longitudinal movement relative thereto, a cam secured to said shaft in operative relation to said abutments, said cylinder being adapted to contain yielding means to actuate said shaft in the direction to retain said cam in contact with said abutments, and work-holding means connected with said shaft.

4. The combination, in an attachment of

1

the class described, with a frame, and a cylinder and cam abutments supported thereby, of a shaft journaled in said frame, and extending into said cylinder, rotary

5 driving means for said shaft, a cam secured to said shaft in operative relation to said abutments, said cylinder being adapted to contain yielding means to actuate said shaft in the direction to retain said cam in contact with said abutments, and work-holding means connected with said shaft, the mechanism being so timed that the shaft and attached parts and members are reciprocated as many times as there are cam changes, at 10 each revolution of the shaft.

18 each revolution of the shaft.

5. The combination, in an attachment of
the class described, with a frame, and a
cylinder and cam abutments supported
thereby, of a shaft journaled in said frame,
20 and extending into said cylinder, a driving
member for said shaft, the latter being
revolvably connected with said driving mem-
ber, but having independent longitudinal
movement relative thereto, a cam secured to
25 said shaft in operative relation to said abut-
ments, a piston on the terminal of said shaft
that is in said cylinder, the latter being
adapted to receive and contain compressed
air between the head thereof and said pis-
30 ton, and work-holding means connected with
said shaft.

35 said shaft.

6. The combination, in an attachment of the class described, with a frame, and a cylinder and cam abutments supported thereby, said abutments being adjustable, of a shaft journaled in said frame, and extending into said cylinder, a driving member for said shaft, the latter being revolutely connected with said driving member, but

40 having independent longitudinal movement relative thereto, a cam secured to said shaft in operative relation to said abutments, said cylinder being adapted to contain yielding means to force said shaft in the direction to

45 retain said cam in contact with said abutments, and work-holding means connected with said shaft.

7. In an attachment, of the class described, a revolute and reciprocable shaft provided with work-holding means, an adjustable cam abutment, a cam mounted on said shaft, and yielding means to retain said cam in contact with said abutment.

8. The combination, in an attachment of
55 the class described, with a frame, and a cyl-
inder and cam abutments supported thereby,
of a shaft journaled in said frame, and ex-
tending into said cylinder, a driving mem-
ber for said shaft, the latter being revolvably
60 connected with said driving member, but
having independent longitudinal movement
relative thereto, a piston on the end of said
shaft that is in said cylinder, a stuffing-box
for said shaft in said cylinder, said cylinder
65 being adapted to receive and contain com-

pressed-air behind said piston, a cam secured to said shaft in operative relation to said abutments, and work-holding means connected with said shaft.

9. The combination, in an attachment of 70
the class described, with a frame, and a cylinder and cam abutments supported thereby,
of a shaft journaled in said frame, and ex- 75
tending into said cylinder, a driving mem-
ber for said shaft, the latter being revolubly
connected with said driving member, but
having longitudinal independent movement
relative thereto, a cam secured to said shaft
in operative relation to said abutments, a
piston on the end of the shaft that is in said 80
cylinder, the latter having inlets for com-
pressed-air and oil behind said piston, a
stuffing-box in said cylinder for said shaft,
and work-holding means connected with said
shaft. 85

10. The combination, in an attachment of the class described, with a frame having projections, and cam-abutment rods adjustably arranged in said projections and provided with anti-friction members, of a shaft journaled in said frame, means to rotate said shaft, a cam on said shaft, and yielding means to urge said shaft in the direction to force said cam into contact with said abutment rods, the latter being parallel with said shaft. 90 95

11. The combination, in an attachment of the class described, with a revoluble and reciprocable shaft provided with a work-holder support, and yielding means to actuate said shaft longitudinally in one direction, of a rocking work holder attached to said support.

12. The combination, in an attachment of the class described, with a revoluble and reciprocable shaft provided with a work-holder support, and yielding means to actuate said shaft longitudinally in one direction, of a work-holder carried by said support, said holder comprising a stud projecting from said support, a block supported by said stud, and means to attach the work to said block. 105 110

13. The combination, in an attachment of the class described, with a revoluble and reciprocable shaft provided with a work-holder support, and yielding means to actuate said shaft longitudinally in one direction, of a work-holder carried by said support, said holder comprising a stud projecting from said support, a block supported by said stud, and means to attach the work to said block, said stud being adapted to rock in said support. 115 120

14. The combination, in an attachment of the class described, with a revoluble and reciprocable shaft, yielding means to actuate said shaft longitudinally in one direction, and a work-holder support mounted on said shaft, of a work holder attached to said support, said holder comprising a bolt having 130

its head secured in said support, and projecting therefrom, a block attached to the outer terminal of said bolt, and yielding means to retain said block in approximately 5 parallel relation with said support.

15. The combination, in an attachment of the class described, with a revoluble and reciprocable shaft, yielding means to actuate said shaft longitudinally in one direction, and a work-holder support mounted on said shaft, of a work holder attached to said support, said holder compressing a bolt having its head confined in said support, and projecting therefrom, the arrangement 10 being such as to permit to said bolt a limited amount of movement, a washer of yielding material encircling said bolt, means secured to said support to retain said washer in place, a block mounted on said bolt and provided with holding means for the work, and yielding means to retain said block in approximately parallel relation with said support.

16. The combination, in an attachment 25 of the class described, with a revoluble and reciprocable shaft, yielding means to actuate said shaft longitudinally in one direction, and a work-holder support mounted on said shaft, of a work holder attached to said support, said holder comprising a bolt having its head in said support and capable of limited movement independently of said support, a block mounted on said bolt, said block being provided with work-securing 30 means, a headed rod slidingly arranged in said support behind said block, a spring interposed between said support and the head of said rod, and means to limit the outward movement of said rod.

17. The combination, in an attachment of the class described, with a revoluble and reciprocable shaft, yielding means to actuate said shaft longitudinally in one direction, and a work-holder support mounted 40 on said shaft, of a work holder carried by said support, said holder comprising a bolt having its head in said support and capable

of limited independent movement relative thereto, a yielding washer encircling said bolt, means attached to said support to 50 secure said washer in place, a block mounted on said bolt, said block being provided with work-attaching means, a headed rod slidingly arranged in said support behind said block, a spring interposed between said support and the head of said rod, and means to 55 limit the outward movement of said rod.

18. The combination, in an attachment of the class described, with a revoluble and reciprocable shaft, yielding means to actuate 60 said shaft longitudinally in one direction, and a work-holder support mounted on said shaft, of a work holder comprising a block carried by said support, and provided with fixed and movable dogs, the 65 movable dog being spring-actuated in one direction, and an eccentric arranged to actuate said movable dog against the force of its spring.

19. The combination, in an attachment of 70 the class described, with a revoluble and reciprocable shaft, yielding means to actuate said shaft longitudinally in one direction, and a work-holder support mounted on said shaft, said support having pins projecting 75 therefrom, of a work holder carried by said support between said pins, and adapted to rock therebetween.

20. The combination, in an attachment of 80 the class described, with a revoluble and reciprocable shaft, yielding means to actuate said shaft longitudinally in one direction, and a work-holder support mounted 85 on said shaft, of a work holder comprising a block carried by said support, and provided with fixed and movable dogs, the movable dog being spring-actuated in one direction, and means to hold said movable dog and actuate the same against the force of its spring.

GEORGE R. BARKSDALE.
